UNITED STATES PATENT OFFICE.

LEOPOLD KABIS, OF CHEYENNE, WYOMING, ADMINISTRATOR OF THOMAS MOORE, DECEASED.

DESIGN FOR AN ARCHED PLATE FOR PACK-SADDLES.

SPECIFICATION forming part of Design No. 29,336, dated September 13, 1898.

Application filed July 27, 1898. Serial No. 687,048. Term of patent 14 years.

To all whom it may concern:

Be it known that THOMAS MOORE, deceased, late a citizen of the United States, and a resident of Cheyenne, county of Laramie and State of Wyoming, duly invented and produced a new and original Design for Arched Plates for Pack-Saddles, of which the following is a full, clear, and exact description, reference being had to the accompanying drawings, forming a part hereof.

Figure 1 is a front elevation of an arched plate for pack-saddles embodying the new design. Fig. 2 is a plan view of the arched plate, and Fig. 3 is a vertical sectional view taken approximately on the line 3 3 of Fig. 2.

As shown in the drawings, the leading or material feature of the design consists of a semicircular plate 1, the opposite edges 2 of which are flanged upwardly, and formed through the ends of said plate are large ap-

ertures 3, and arranged in the body of the plate between said apertures 3 are the smaller apertures 4. Extending downwardly and outwardly from the lower ends of the semicircular plate 1 are the wedge-shaped arms 5, and extending downwardly and outwardly from the lower ends of the arms 5 are the apertured arms 6.

What is claimed is—

The design for an arched plate for pack-saddles, substantially as herein shown and described.

In testimony whereof I affix my signature in presence of two witnesses.

LEOPOLD KABIS,
Administrator of Thomas Moore, deceased.

Witnesses:

WALTER R. STOLL,
WM. R. SCHNITGER.
